ELECTRIC SANDING MACHINE

Sarkis Doctor Acopian, Easton, Pa., assignor to Weller
Electric Corporation, Luquillo, Puerto Rico, a corpora-
tion of Puerto Rico

Application August 17, 1955, Serial No. 37,537

Term of patent 14 years

(Cl. D37—1)

Fig. 1.

Fig. 2.

Fig. 3.

Figure 1 is a perspective view of an electric sanding machine embodying my new design, as seen from one side thereof;

Figure 2 is a side elevation thereof, as seen from the opposite side thereof; and

Figure 3 is an end elevation thereof, as seen from the left hand side of Figure 2.

I claim:

The ornamental design for an electric sanding machine, as shown.
